Henry Behn

United States Patent Office.

HENRY BEHN, OF NEW YORK, N. Y.

Letters Patent No. 62,998, dated March 19, 1867.

IMPROVED BURGLAR ALARM.

The Schedule referred to in these Letters Patent and making part of the same.

TO ALL WHOM IT MAY CONCERN:

Be it known that I, HENRY BEHN, of New York, in the county and State of New York, have invented a new and improved Burglar Alarm; and I do hereby declare that the following is a full and exact description thereof, reference being had to the accompanying drawings, and to the letters of reference marked thereon.

Figure I represents a front view of the alarm; and

Figure II is a section through the line III and IV.

The nature of my invention consists in the arrangement of an alarm bell, operated by the turning of the knob of the lock, in combination with a pendulum, which is made to swing backwards and forwards so as to strike the alarm bell by each vibration.

In the accompanying drawings, A represents a plate, to which the different levers, hammers, with their springs, stops, &c., are attached, as well as the alarm bell B. This alarm bell B is provided with a long screw, α , firmly attached to the same, which passes through a suitable boss, n , on the plate A, and is screwed into the wooden door D, (see Fig. II.) By this arrangement the whole mechanism fastened to the plate A, together with this alarm bell B, is secured to the door by means of this single screw α , facilitating thereby the attachment of this alarm in any desired position. On the plate A a lever, C, is arranged, turning on a suitable centre, s , and operating the bell-hammer E whenever said lever C is put in motion. To the knob of the lock F, arms, G and G', are attached by means of a screw or pin, m , one arm standing upwards, and the other arm downwards. These arms G and G' are connected, by means of the rods J J', with the lower end of the lever C, in such a manner that when the knob of the lock F is turned either towards the right or towards the left for the purpose of opening the door, either the rod J or the rod J' shall move the lever C, so as to operate the bell-hammer E, giving thereby the desired alarm whenever the knob of the lock is turned. H is a pendulum, turning on a suitable centre, v , fast to the plate A. N is a stop-lever, by which the pendulum H can be held in a horizontal position, as represented in the drawing. On the lever C a projection, w , is made, which, as soon as the lever C is put in motion by the turning of the knob of the lock, as above described, will come in contact with this stop-lever N, and move the same clear of the end of the pendulum H, allowing thereby said pendulum to fall downwards and vibrate several times between the lines 2 and 3, operating, by each vibration, the alarm-hammer L, thus giving three or four additional alarms on the bell B, independently of the alarm given by the direct motion of the lever C. When it is desired to disconnect this additional alarm, the pendulum H is allowed to hang downwards, as shown in dotted lines. To disconnect the alarm, the pin or screw m is removed or loosened, when the knob of the lock can be turned, for the purpose of opening the lock, without operating the arms G and G', and consequently the alarm.

What I claim as my invention, and desire to secure by Letters Patent, is—

1. The arms G and G', rods J J', and lever C, operating the bell-hammer through a lug, adjusted, combined, and arranged substantially as specified.
2. I claim the arrangement of the pendulum H, in combination with the stop-lever N, operated by a projection, w , fast to the lever C, in the manner and for the purpose as set forth.

HENRY BEHN.
